Chinese Search Report dated Mar. 7, 2019 in connection with Chinese Patent Application No. 201730633615.2.

Primary Examiner — Terry A Wallace(74) *Attorney, Agent, or Firm* — Westbridge IP LLC(57) **CLAIM**

The ornamental design for a seal pot, substantially as shown and described.

DESCRIPTION

FIG. 1 is a top perspective view of a seal pot showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in the figures depict portions of the seal pot that form no part of the claimed design.
